CLAIM

The ornamental design for a surgical headlight or similar article, substantially as shown and described.

DESCRIPTION

FIG. 1 is a right side perspective view of the surgical headlight or similar article showing our new design; FIG. 2 is a cross sectional view taken through line 2—2 of FIG. 1 on an enlarged scale

FIG. 3 is a left side perspective view;

FIG. 4 is a front plan view;

FIG. 5 is a rear plan view;

FIG. 6 is a cross sectional view taken through line 6—6 of FIG. 5 on an enlarged scale

FIG. 7 is a top plan view; and

FIG. 8 is a bottom plan view.
